(57) **CLAIM**

The ornamental design for a transducer mounting bracket, as shown and described.

DESCRIPTION

FIG. 1 is a perspective view of a transducer mounting bracket embodying my design;

FIG. 2 is a top view of the transducer mounting bracket;

FIG. 3 is a left side view of the transducer mounting bracket;

FIG. 4 is a front view of the transducer mounting bracket;

FIG. 5 is a right side view of the transducer mounting bracket;

FIG. 6 is a rear view of the transducer mounting bracket; and,

FIG. 7 is a bottom view of the transducer mounting bracket.
